UNITED STATES PATENT OFFICE.

JOHN McCLOSKEY, OF BOSTON, MASSACHUSETTS, ASSIGNOR OF ONE-HALF TO
CHARLES F. FARWELL, OF SAME PLACE.

EXPANSION DEVICE.

SPECIFICATION forming part of Letters Patent No. 398,525, dated February 26, 1889.

Application filed August 25, 1888. Serial No. 283,700. (No model.)

To all whom it may concern:

Be it known that I, JOHN McCLOSKEY, of Boston, in the county of Suffolk and State of Massachusetts, have invented a new and Improved Expansion Device, of which the following is a specification.

My invention consists of a tube whose sides are provided with one or more convolutions, each extending around the tube, and each independent of the others, and of such a shape that a longitudinal section of the tube presents two convolutions or series of convolutions, each convolution being of the shape of a double **C** spring or curve, and the series on each side being the reverse of—*i. e.*, the reverse of parallel with—the series on the opposite side. These convolutions are not spiral, each being on an independent circle or an independent plane, and do not extend so far toward the center of the tube but that a straight line may be drawn longitudinally through said center without coming in contact with a convolution. This may be used in various connections where it is desired to convert force or pressure into motion. For example, it may be filled with any of the hydrocarbons—such as rhigoline, naphtha, gasoline, &c., any of which are highly expansible by application of heat—and after having been sealed tightly, in any manner desired, will elongate from the expansive pressure generated within said tube upon the application of heat. This it is enabled to do by the shape of said convolutions or reverse **C**-curves in the side walls of said tube. Upon the removal of the force or pressure the spring or power of the material of which the tube is made may cause said tube to return or contract to its original length, thus converting force into reciprocal motion; or said tube may be made to return to its original length by means of a counter-pressure acting upon the outside thereof.

Heat may be applied to the device in any desired manner, such as in the shape of a naked flame or by radiation, steam, electricity, hot air, &c.

In the accompanying drawings, in which similar letters of reference indicate like parts, Figure 1 shows a longitudinal section of a steam-regulator valve provided with my de-

vice. Fig. 2 is a longitudinal section of my device applied to a steam-pipe joint. Fig. 3 is a longitudinal section of the device placed on the end of a pipe.

In Fig. 1, A is the casing; B, the inlet-tube; C, the outlet-tube; D, the regulating-screw turned by the hand-wheel D'; E, the stuffing-box, and F the valve upon the valve-seat, all constructed as usual and making no part of the invention. H is a tube whose sides are formed into the series of independent annular convolutions H' of the shape of double reverse **C** curves or springs. As will be seen, the two series exhibited by the sectional view are the reverse of—not parallel with—each other. Each convolution is on a true circle, and a central passage is left clear longitudinally through the tube. This tube is in this figure to be filled with any desirable liquid, preference being given, of course, to those that are highly expansible by the application of heat, and is provided with one or more inlets for the admission of the liquid, said inlets being preferably near the ends of the tube, and being provided with suitable sealing-stoppers, as h, whereby any possibility of leakage is prevented. Any well-known liquid-tight sealing device may be employed in place of the simple stopper shown in the drawings. Now by applying heat to this tube in any manner, whether in the form of steam, electricity, or other substance, the tube will expand by the pressure or stretching of the **C**-curves, which form the annular convolutions H' in an exact longitudinal line—that is, a line drawn centrally through the tube—so that if the valve H, which is secured to the lower end of the tube, were raised from its seat and steam let in through the port B the tube whose upper end is secured to the lower end of the regulating-screw D would expand longitudinally and force the valve down upon its seat, while as the temperature within the casing lowered the tube would contract and the valve be lifted from its seat, letting in more steam.

In Fig. 2, I and J are steam-pipes, and K K the collar forming the joint cut into two parts to allow the application of my tube H, which has in this instance but a single convolution, H'. In this case the tube is open at both ends to allow the passage of the steam, and

is practically an expansion-joint, the movement whereby the tube is elongated and shortened being derived from the contraction and elongation of the pipes I J.

5 In Fig. 3 the tube is secured to the end of a pipe, L, and is closed at its free or outer end. Elongation of the tube H by the application of heat—say to the contents of the pipe L—produces motion at the free closed end of said

10 tube H.

I do not claim as new an annular convolution, even though said convolution may be in section of the shape of a curve or arc of a circle. My convolutions are C-shaped, double and reverse—*i. e.*, each convolution is of the shape of an arc of a circle which is greater than a half-circle, (which is what I intend to convey by "C-shaped")—and in each convolution are portions of two other arcs reversed, which 20 when completed, form the greater part of the next convolutions. By this means, and because in each convolution there are no straight portions, but only true arcs, each more than half a circle, the expansion or lengthening of 25 the tube is not only greatly enhanced, but the bending and strain of the convolutions are distributed as the tube is lengthened by the application of heat.

There are many positions and places in 30 which my peculiarly-shaped tube may be set; but wherever the device is placed, and in whatever manner force is applied, the same result is obtained—viz., longitudinal expan-

sion or lengthening of the tube, whereby its ends are forced away from each other on a 35 straight line.

Any desirable material, whether metallic or otherwise, may be used in the construction of the tube.

Having thus fully described my invention, 40 what I claim, and desire to secure by Letters Patent, is—

1. The herein-described expansion device, consisting of a tube whose sides are formed externally and internally into one or more annular convolutions of the shape in section of reverse C curves or springs—*i. e.*, arcs comprehending more than semicircles—whereby longitudinal expansion or lengthening of the tube may be obtained, substantially as set 45 forth.

2. The herein-described expansion device, consisting of a tube closed at its ends and whose sides are formed externally and internally into one or more annular convolutions 50 of the shape in section of reverse C curves or springs—*i. e.*, arcs comprehending more than semicircles—said tube containing liquid, whereby by the application of heat longitudinal expansion or lengthening of the tube may 55 be obtained, substantially as and for the purpose hereinbefore described.

JOHN McCLOSKEY.
